UNITED STATES PATENT OFFICE.

JAMES WHITE PROVAN, OF OSHAWA, AND JOHN W. PROVAN, OF TORONTO, ONTARIO, CANADA; SAID JOHN W. PROVAN ASSIGNOR TO SAID JAMES WHITE PROVAN.

HAY-CARRIER.

SPECIFICATION forming part of Letters Patent No. 340,923, dated April 27, 1886.

Application filed January 22, 1886. Serial No. 189,369. (No model.)

To all whom it may concern:

Be it known that we, JAMES WHITE PROVAN, of the town of Oshawa, in the county of Ontario, in the Province of Ontario, manufacturer, and JOHN WHITE PROVAN, of the city of Toronto, in the county of York, in the Province of Ontario, Canada, salesman, have jointly invented certain new and useful Improvements in Hay-Carriers, of which the following is a specification.

The object of the invention is to design a simply-constructed hay-carrier, preferably reversible; and it consists in the formation and arrangement of parts hereinafter more particularly specified.

Figure 1 is a side elevation showing our improved hay-carrier in position on its supporting-rod and locked to the stop-block. Fig. 2 is a longitudinal section of the hay-carrier. Fig. 3 is a perspective detail of the reversible head to which the bale-rope is attached. Fig. 4 is a perspective detail of the body-plate, having pivoted to it the bell-crank bracket, which forms the latch and carrier-wheels' journals. Fig. 5 is a perspective detail of the trip-bar and bail supporting hook. Fig. 6 is an enlarged sectional detail of the stop-block. Fig. 7 is a detail of the bail. Fig. 8 is a detail of the bell-mouth bracket.

A represents a portion of the supporting-rod, which is supported in the barn in the ordinary way.

B are the carrier-wheels provided with axles C, forming part of or connected to the arms D, which form part of or are connected to the crank-brackets E, the other arm of which forms the latch F, the said brackets E being pivoted at a on the body-plate G, as shown, so that a vertical center line drawn through either of the axles C would pass outside of the center of its pivot a. Consequently the weight of the carriage which is supported by these axles has a tendency to hold the outer end of the latch F upwardly, causing the latch F to snap under the stop-block Q and be held in rigid connection by the weight of the load without the necessity of any spring. The bottom of the body-plate G has a flange, b,

formed round a hole made in its center, and a corresponding flange is made on the top side 50 of the head H, the said flanges being made strong to support the weight of the load, which is carried, as hereinafter described, by the said head H. This head H is made substantially as shown in the drawings, a projection, 55 d, being made on one side of it to support the eye I of the bale or draft rope J. An extension, e, is formed on the side of the head H opposite to the projection d, in which extension the sheave-pulley K is journaled, as indicated. By thus carrying the load entirely by the head H, which is pivoted, as shown, on the bottom of the body-plate G, the said head may be swiveled around without interfering with the latches F, which, as before described, 60 are pivoted upon the body-plate G.

We pivot the bail-supporting hook L on a hub, N, formed on the trip-bar M, and provide a spring, O, designed to hold the hooked end of L toward the side of the bell-mouth f, which 70 is made off the center of the head H. The spring O also holds one end of the trip-bar M outside of that end of the body-plate G where it is desired to effect the trip. A tail, p, formed on the back of the hook L, projects between 75 guides q, formed on the inside of the head H, so that the hook L must revolve with the said head. When the bail P enters the bell-mouth f of the head H, it is guided by the said bell-mouth shape toward the bail-supporting hook L, which springs back to permit it to pass, and is then thrown into the bail by the action of the spring O. When the end of the trip-bar M strikes the stop-block Q, the supporting-hook J, which is attached to the 80 trip-bar M, is pushed out of the bail, allowing the bail to fall out clear of the support specified. Owing to the fact that the bell-mouth is on one side of the hole around which the head H is pivoted, and that the supporting-hook L is held against that side by the spring O, the trip-bar M is moved longitudinally when the head H is turned on its pivot, 85 as the said trip-rod M is connected to the supporting-hook L. Consequently every time 90 that the head is turned round its pivot the

trip-bar M is adjusted, so that the trip-bar M will operate from the end opposite to that to which it has been previously set.

In addition to the arms D and F, each crank-bracket E has attached to or formed upon it an arm, R, which extends back and is bent so as to project through the hole in the body-plate G, the end of the said arm R being in such a position that when the bail P passes to the hook L the said bail must come in contact with the end of the arm R, and as this arm R is attached to or forms part of the bracket E the said bracket is rocked on its pivot *a*, so as to carry the latch F clear of the stop-block Q, thus releasing the carriage and permitting it to be drawn back on the rod A.

In order to permit the arms R to enter the hole in the head H, we make slots *g* in the trip-bar, and, with the view of preventing the arms R gripping or binding the trip-bar M, we form on each arm R a lug, *h*, which butts against the top of the body-plate G and holds the arms R clear of the trip-bar M. On each end of the trip-bar M we form a heavy flange, *i*, through which the end of the trip-bar passes. These flanges also serve the purpose of a butting-block to receive the shock when the end of the body-plate G strikes the end collar-beam used in supporting the ends of the rod A.

In Fig. 6 we show a detail of the stop-block, which is the same as that described in United States Patent No. 322,968, except that it has the following improvement: We cast or otherwise attach onto the end of the lever *j* a projection, *k*, which, if the lever is jerked, will strike against the latch *i* and knock it clear of the end of the lever *j*, permitting the latter to drop down free. By this arrangement the extra rope necessary to unlatch the stop-block described in Patent No. 322,968 is dispensed with. We may also mention the fact that the latch F would be operated by the weight of the carriage even if the pivot-point *a* were directly upon the center line drawn through the axle C.

On reference to Figs. 3 and 8 it will be noticed that the bell-mouth opening *f* in the head H is an arc of a circle, which at the point where the supporting-hook L projects is made in size and shape to correspond with the bail P, the top of which, as shown in Fig. 7, corresponds with the circle of the mouth *f*, while the side bars of the bail fit against the cord of the arc. Consequently when the bail enters the mouth its head or top bar, *m*, is guided directly over the hook L, the inside of the bar *m* being concaved, corresponding substantially to the outside circle of the said bar, so that when the bail enters the head no part of the bail can come in contact with the spring O or head of the bolt securing the hook L.

What we claim as our invention is—

1. A hay-carrier in which the supporting-wheel is connected to an arm attached to or forming part of the latch, which latch is pivoted to the body-plate, combined with a sup-

porting-eye independent of said latch, substantially as and for the purpose specified.

2. In a hay-carrier, the body-plate and the wheel, arm, and latch pivoted to the body-plate, in combination with a head arranged to support the eye and sheave-pulley of the bale or draft rope, and so connected to the body-plate that it will revolve thereon independent of the latch, substantially as and for the purpose specified. 70 75

3. In a hay-carrier, a body-plate, G, on which the latches F are pivoted, in combination with the head H, arranged to support the bale-rope eye I and sheave-pulley K, the said head being pivoted upon the body-plate G independent of the latches, substantially as and for the purpose specified. 80

4. In a hay-carrier, a body-plate, G, on which the latches F are pivoted, and the trip-bar M, adjustably supported, in combination with a head, H, arranged to support the bale-rope eye I and sheave-pulley K, the said head being pivoted upon the body-plate G, substantially as and for the purpose specified. 85 90

5. In a hay-carrier, a trip-bar, M, adjustably supported upon the body-plate G, and having a projection formed upon or attached to it, to project through a hole in the said body-plate, and supporting the hook L, in combination with the head H, supported by an annular flange, *b*, formed on the body-plate G, and a spring, O, arranged to act on the hook L, substantially as and for the purpose specified. 95 100

6. The combination, with the trip-bar M and swiveled head H, of supporting-hook L, pivoted to the trip-bar M, and provided with a tail, *p*, arranged to engage with the guides *q*, formed on said head H, substantially as and for the purpose specified. 105

7. A latch, F, connected to or forming part of the arm D, which carries the wheels B, and is pivoted on the body-plate G, in combination with an arm, R, designed to extend through a hole in the body-plate G immediately over the bell-mouth opening *f*, formed in the head H, substantially as and for the purpose specified. 110

8. A head, H, supported on an annular flange, *b*, formed on the body-plate G, and having a bell-mouth opening, *f*, formed in it on one side of or off the center of the annular flange *b*. 115

9. A latch, F, connected to or forming part of the arm D, which carries the wheels B, and is pivoted on the body-plate G, in combination with an arm, R, designed to extend through a slot, *g*, in the trip-bar M, and provided with a lug, *h*, to strike the top surface 120 of the body-plate G, substantially as and for the purpose specified. 125

10. In a hay-carrier, a body-plate, G, having a flange, *i*, formed on each end of it to support the trip-bar M, and an annular flange, *b*, to support the head H, substantially as and for the purpose specified. 130

11. In a stop-block formed by a stop-lever, *j*, supported by the latch *i*, the combination of a projection formed upon one of said parts, so that the upward movement of the lever above the hook on the latch will push the said hook clear of the lever, substantially as and for the purpose specified.
12. In a hay-carrier, an arm carrying the supporting-wheel, and a latch rigidly attached to or forming part of said arm and pivoted to the body-plate, substantially as and for the purpose specified.

Toronto, November 20, 1885.
